DESIGN FOR A ROLL-TOP PLAYING CARD BOX

Harvey Lathrop, Forest Hills, N. Y.

Application April 24, 1937, Serial No. 68,965

Term of patent 14 years

To all whom it may concern:

Be it known that I, Harvey Lathrop, a citizen of the United States, residing at Forest Hills, Long Island, county of Queens, State of New York, have invented a new, original, and ornamental Design for a Roll-Top Playing Card Box, of which the following is a specification, reference being had to the accompanying drawing, forming part thereof.

I claim:

The ornamental design for a roll-top playing card box, substantially as shown and described.

HARVEY LATHROP.
